CLAIM

The ornamental design for a cover for a non-lethal gun magazine, as shown and described.

DESCRIPTION

FIG. 1 is a perspective elevated view of a cover for a non-lethal gun magazine, showing our new design;

FIG. 2 is a front view thereof;

FIG. 3 is a back view thereof;

FIG. 4 is a top side view thereof;

FIG. 5 is a bottom side view thereof;

FIG. 6 is a left side view thereof; and,

FIG. 7 is a right side view thereof.

The dash-dot broken lines in FIG. 4 disclose a section cut plane and form no part of the claimed design.
